Des. 185,800
Patented Aug. 4, 1959

185,800

DRESSER CADDY

Albert N. Brooks, Lincolnwood, Ill.

Application November 28, 1958, Serial No. 53,552

Term of patent 7 years

(Cl. D29—23)

Des. 185,800

PAGE 2

FIG. 3.

Fig. 4.

Fig. 5.

Fig. 6.

Fig. 1 is a perspective view of a dresser caddy, showing my new design;

Fig. 2 is a front elevational view thereof;

Fig. 3 is a rear elevational view thereof;

Fig. 4 is a left side elevational view thereof;

Fig. 5 is a right side elevational view thereof; and

Fig. 6 is a top plan view thereof.

The bottom of the design is plain and unornamented.

I claim:

The ornamental design for a dresser caddy, as shown and described.
